UNITED STATES PATENT OFFICE.

BENJAMIN S. REYNOLDS, OF MILWAUKEE, WISCONSIN, ASSIGNOR TO CHAIN BELT COMPANY, OF MILWAUKEE, WISCONSIN, A CORPORATION OF WISCONSIN.

FLUME-SCREEN.

1,208,655.

Specification of Letters Patent. Patented Dec. 12, 1916.

Application filed October 4, 1916. Serial No. 123,692.

To all whom it may concern:

Be it known that I, BENJAMIN S. REYNOLDS, a citizen of the United States, residing at Milwaukee, in the county of Milwaukee and State of Wisconsin, have invented 5 certain new and useful Improvements in Flume-Screens, of which the following is a specification.

My invention relates to flume screens such 10 as are used to take from water drawn off from streams to be used for industrial purposes, the solid objects that may be objectionable or injurious if delivered to the apparatus where the water is used; and it has 15 for its object to improve the apparatus and the screens constituting parts of the apparatus, in the manner to be hereinafter pointed out.

In the accompanying drawings—Figure 20 1 is a vertical sectional view of apparatus constructed according to my present improvements. Fig. 2 is a plan view of the installation shown in Fig. 1. Fig. 3 is an elevation of a portion of a flume screen drawn 25 on a larger scale than Fig. 1 in order to illustrate certain of the improvements. Fig. 4 is a transverse sectional view taken on the line IV—IV of Fig. 3. Fig. 5 is a longitudinal sectional view taken on the line V—V 30 of Fig. 3. Fig. 6 is a longitudinal sectional view illustrating a feature of the improvement not shown in any of the other views. Fig. 7 is a vertical sectional view of the lower portion of the screen and the guard 35 that is associated therewith when the screen is let down to its lowermost position.

In my Patent No. 1,191,115, dated July 11, 1916, I show a vertically adjustable water screening apparatus supported adjacent to a 40 wall in which are formed two openings, through the lower of which the water to be screened passes when the water in the stream is low, and through the upper of which the water to be screened passes when the water 45 is high; an adjustable gate for closing one or the other of the openings at will; and means for vertically adjusting the screening apparatus as a whole to bring it into operative position relative to the uncovered opening.

50 It is sometimes desirable to employ a vertically adjustable screen, such as shown in my aforesaid patent, where the wall separating the stream from which the water is taken from the chamber in which the screen 55 is located has but a single communicating

opening, as for instance when a short, vertically adjustable screen, such as my invention permits the use of, is set up in a chamber that might have been originally constructed to receive screening apparatus of a different 60 type. My said patent shows the screen supported close against the face of the wall in which is located the two openings. If, however, the screen be located some distance back from the wall a single opening arranged through the wall at a low level may 65 be sufficient, as I will now explain.

Referring to Figs. 1 and 2, 13 indicates a wall separating the chamber 14 in which the screen is located, from the stream from 70 which water is taken and delivered in purified condition to the plant, through the intake conduit 15. In the lower portion of the wall 13 there is a communicating opening 16 between the stream and the chamber 14. 75 The screen, indicated as a whole by 17, is similar to that described and illustrated in my aforesaid patent, and hence need not be herein described in detail. Suffice it to say it is of the endless automatically cleaned 80 flume screen type, having articulated screen sections united by chains which pass about upper and lower wheels 18 suitably supported in the rigid screen framework 19. The screen is relatively short between the 85 turning wheels, and is vertically adjustable within the chamber 14 as described in my aforesaid patent. Vertical guides 20 direct the up and down movements of the screen as a whole and may also serve as the means for 90 preventing water from passing between the vertical sides of the screen and the side walls of the chamber 14. Means for vertically adjusting the screen are not shown in detail, being typified by the hoisting cables 21, one 95 of which appears in Fig. 1. Neither are the means by which the endless screen is moved, nor the means for cleaning the sections of the screen, illustrated, as these are well known in the art and form no feature of the 100 present invention.

22 indicates a vertically adjustable gate; 23, guides by which its vertical movements are controlled and directed; and 24 a screw rod by which it may be moved up and down. 105 This gate is of approximately the same width as the screen 17 and is of a height corresponding with the distance to which it may be desired to move the screen upward from its lowermost working position. 110

At low stages of water in the stream the screen is let down to the bottom of the chamber 14 and the gate is raised, the water then taking a comparatively straight course from the stream, through the opening 16, the chamber 14, where it is screened, and into the conduit leading to the plant where the water is to be used. When the water in the stream rises to such a height as to make it impracticable to use the parts when in the position just described, the screen is lifted into the position indicated in Fig. 1, and the gate 22 is lowered to close the space between the bottom of the screen and the bottom of the chamber 14. The water is now caused to take the tortuous path indicated by the arrows in Fig. 1. To permit the water to pass freely along the course just indicated it is necessary that the screen shall be set back from the wall 13 sufficiently far to provide a free passage between the wall and the screen for the volume of water that the screen will treat.

The guides 23 may be on either side of the screen; or two sets of guides may be used as shown in the drawings, one on each side of the screen. It is largely immaterial whether one set or the other of these guides is used, or whether both sets are used, two gates, one on each side of the screen, being employed in the latter instance.

25, 25 indicate the gutters for receiving and carrying away refuse removed from the screen surface.

30 The screening surface of the screen 17 is made up of a series of separate articulated screen sections 2 having suitable rectangular marginal frames 3, which are, in turn, secured to endless chains 4. These chains pass around and engage with the wheels 18. The frames for the separate screens are supported so as to come together edge to edge, as near as may be, and the spaces between them are covered, when the 35 screen sections are in working position, by strips 5. The chains 4 preferably carry rollers 6 that are adapted to run upon tracks 7, such as formed by the angle irons shown in the drawings. As in use the screen is usually arranged vertically or at a steep angle, I employ lips 9 to catch the material that may be separated by the screens and which when lifted above the surface of the water would fall backward and downward 40 from the screen surfaces, and hence would not be carried off, were conveying means like the lips 9 not employed to catch and carry it. These lips are disposed at an angle to the surfaces of the screens 2 and are 45 preferably secured to the lower transverse edges of the frames 3 of the up-moving sections 2.

In order to prevent material that is floating or suspended in the stream, from passing 50 around the side edges of the screen, I

provide the guards 8. These, preferably, are plates secured to the screen framework 19 and parallel with and overlying the tracks 7, and at such distance therefrom as to be as close to the upper edges of the 55 screen frames 3 as is practicable and yet permit the free movements of the working parts. The guards extend inwardly sufficiently far to overlie the side edges of the screen sections at all times. Experience has demonstrated that in operating flume screens of the character illustrated and described herein there must be a certain amount of clearance between the outer ends of the pintles 10 that unite the links of the chains 4, and 60 the supporting portions or flanges 11 of the guards 8, as it is practically impossible to make a screen that will run easily without allowing it a certain amount of side or transverse flexure. The guards must therefore overlie the screen sections sufficiently to 65 completely cover their edges should the screen move laterally toward either side to the maximum extent permitted. In order that the lips 9 shall clear the edges of the 70 guards 8 as the screen shifts sidewise during use, these lips are made of less width than the transverse dimensions of the screen, that is, they are cut away at their ends so as to leave a certain amount of clearance between 75 them and the edges of the guards 8, as indicated at 12.

By the arrangement described and illustrated I am enabled to bring the guards 8 so close to the screen that they operate effectively to prevent any material that the screen is supposed to remove from passing around the edges of the screen, thus overcoming an objection incident to screens of this character as heretofore constructed.

80 The strips 5 operate to prevent the passage of coarse material between contiguous screen sections and are preferably secured to the outer faces of the lips 9, and of the same transverse length, crosswise of the screen as 85 a whole, as are the lips.

85 Filling pieces 26 are interposed between the ends of the lips 9 and the frames 3 to give a firm support to the former when their ends are cut off so as not to extend to 90 the edges of the frames 3.

95 It sometimes becomes necessary to stiffen the traveling screen transversely, particularly where the screen sections are wide, and for this purpose I prefer to employ transverse rods 27 between the chains 4, locating such rods between the ends of certain of the screen sections 2 as represented in Fig. 6. While this arrangement operates to separate the screen sections between which the rods pass, I utilize these rods to fill, as nearly as is practical, the spaces between the sections, mounting them concentric with the axes of articulation of the screen sections and the 100 chains. If desired a filling tube 28 may be 105

5 mounted upon the rod 27. The rod 27, or the rod and the tube 28 together, will operate to prevent solid material passing between the screen sections, and it has been found that the joints may in this way be made so close that the strips 5 may be dispensed with.

Under certain conditions it is found desirable to interpose between the lower end 10 of the screen 17 and the bottom of the chamber 14 means that will prevent solid material passing the lower end of the screen when let down to its lowermost position, and such an arrangement I have represented 15 in Fig. 7, where 29 designates a curved guard secured to the bottom of the chamber 14, and substantially concentric with the axis of the lower wheel 18 in the position it occupies when the screen is let down to 20 its lowermost position. The guard 29 should be of sufficient length to insure that under all circumstances at least one of the projecting lips 9 is in proximity to its inner curved face (although it may be so long 25 that several of the lips are simultaneously traveling adjacent thereto as represented in Fig. 7), so that while more or less water may pass the lower end of the screen no solid material of harmful size will be allowed to pass.

30 The several improvements presented in this case have been devised to meet practical difficulties met with in operating water screening apparatus, and are effective for 35 the purposes for which they are intended, and at the same time add but little to the cost of the apparatus.

What I claim is:—

1. In a water screening apparatus, a 40 water chamber separated from the stream from which the water supply is taken by a wall, in the lower portion of which is an opening, a vertically adjustable water screen mounted in the chamber at a distance back 45 from the wall sufficient to permit a free flow of water between the screen and the wall, and a gate for closing the space between the bottom of the screen and the bottom of the chamber arranged to deflect the 50 water upward to cause it to pass through the screen when the latter is raised and the gate lowered.

2. The combination with an endless traveling flume screen provided with transverse lips for lifting material taken out of the 55 water by the screen, of means arranged to cover the lateral edges of the screen arranged to prevent material which the screen is intended to separate from passing beyond the said lateral edges, the said lifting lips 60 being shorter than the transverse dimensions of the screen, whereby they lie between the edges of the said covering means.

3. The combination with an endless traveling flume screen formed of separate screen 65 sections connected at their edges to chains, and provided with transverse lips for lifting the material taken out of the water by the screen, of guard plates overlying the lateral edges of the screen and disposed 70 close to the outer edges thereof, the said lifting lips being shorter than the transverse dimensions of the screen and than the distance between the edges of the opposite guard plates, whereby limited lateral flex- 75 ure of the screen is permitted.

4. The combination with an endless traveling flume screen formed of articulated sections, of guards arranged to overlie the lateral edges of the screen and disposed close 80 thereto, transverse lips for lifting material taken out of the water by the screen, the lifting lips being shorter than the transverse dimensions of the screen and than the distance between the opposite edges of the 85 guards, and strips arranged to overlie the spaces between contiguous screens secured to the said lips and also shorter than the distance between the guards.

5. In a flume screen, the combination of a 90 series of separate screen sections, chains at the side edges of the screen to the links of which the screen sections are united, and cross bars uniting the opposite chains and passing between adjacent screen sections, 95 the cross bars being proportioned to the space between the screen sections which they separate as set forth, whereby they substantially fill the spaces between the ends of the sections and operate to prevent solid material that may be carried by the water passing between the said sections and hence escaping the screen.

BENJAMIN S. REYNOLDS.
